United States Patent

Des. 242,278
Patented Nov. 9, 1976

242,278

PORABLE LIGHT

Thomas N. Zelina, Erie, Pa., assignor to
Lighting Systems, Inc., Erie, Pa.

Filed Dec. 4, 1975, Ser. No. 637,764

Term of patent 14 years

Int. Cl. D26—02

U.S. Cl. D48—24 R

FIG. 1.

FIG. 2.

FIG. 3.

FIG. 4.

FIG. 1 is an isometric view of a portable light showing my new design.

FIG. 2 is a side elevational view thereof.

FIG. 3 is a rear elevational view thereof.

FIG. 4 is a top plan view thereof.

The undisclosed side of the light is a mirror image of FIG. 2.

I claim:

The ornamental design for a portable light, as shown and described.
